UNITED STATES PATENT OFFICE.

WILLIAM G. COUGHLIN, OF PHILADELPHIA, PENNSYLVANIA.

RAIL.

Application filed November 2, 1926. Serial No. 145,883.

This invention relates to railroad rails and particularly to a compound rail made up of a base, and a head section which may be detachably secured to the base.

- 5 One object of this invention is to provide a rail having a base which may be permanently secured to the ties and upon which the head section of the rail which receives wear may be readily secured or removed.
- 10 Another object is to provide such a rail in which the area or size of the head is small compared to the base or support so that only a relatively small amount of metal need be scrapped when the head wears out and has 15 to be replaced or re-surfaced.

Another object is to provide base and head sections of such shapes that in their manufacture they may be rolled upon their bearing or wearing surfaces in order to give such 20 surfaces a compact and homogeneous texture.

Another object is to provide such a rail base which is adapted to carry different forms of head sections including heads cut 25 from old rail and a base which has a relatively wide supporting surface upon which the head firmly rests so that any shearing stresses on the metal of the base or head are avoided.

30 A further object is to provide a compound rail in which the base is relatively wide compared to the height, thus providing great strength and rigidity in the rail to oppose lateral forces tending to overturn the rail.

35 Also it is an object to provide novel means for attaching the head section to the base which will effectively resist horizontal thrust against the head section tending to force the same from the base.

40 Other objects and various features of novelty will be apparent to those skilled in the art from the following description read in conjunction with the drawings, in which:

Figure 1 is a transverse section showing an 45 embodiment of this invention with one form of rail head section;

Figure 2 is a similar section with guard rail omitted showing a head section formed of old rail;

50 Figure 3 is a section similar to Fig. 2 showing a modified form of fastening device;

Figure 4 is a side elevation of the construction as shown in Fig. 1 or Fig. 2; and

55 Figure 5 is a side elevation of the Fig. 1

construction but showing the base in discontinuous sections.

Referring to the construction illustrated in Figs. 1 and 4, there is a base 10 and a wearing head section 11 detachably connected thereto. The base 10 is formed in the shape of an inverted U and may be of any desired size. This particular shape permits a wide base as the legs of the U may be spaced apart to any extent desired, thus 60 forming a stable support for the rail. It is to be noted that the base 10 has a top surface or seat 10^a which is of considerable width thus providing a substantial seat for the rail head carried thereon. The base is 70 preferably a rolled section and has no re-entrant projections on its sides and so may be produced by upper and lower rolls in the position in which it is adapted to be used, that is, the lower roll will be beneath the 75 base flanges of the two legs and have a flange pressing out the interior of the U while the mating upper roll will form the upper contours of the base including the top surface 10^a. In this way the greatest pressure is brought to bear upon the top surface where the greatest homogeneity or compactness of metal is desirable. The usual method of rolling rail sections on the sides is liable to, and most frequently does, leave flaws on 80 the top surface where the metal is wedged in sidewise rather than rolled down from above. The top surface 10^a has faces having a slight inclination from each side toward the center of the base and there is a central longitudinal groove 10^b disposed along the center 85 between the sloping portions of the top surface. This groove preferably has substantially parallel and vertical sides, the purpose of which will be apparent as the description 90 proceeds.

The top surface of the head section 11 is that portion of the rail which receives the wear of the wheels, and for this reason the head section is preferably made of harder 100 metal than the supporting base 10. Preferably also the area or size of the wearing head section is comparatively small so that when this portion of the rail wears out or needs re-surfacing only a small amount of metal 105 has to be scrapped or re-rolled as the case may be.

The rail head section 11 shown in Fig. 1 has a pair of heads 12 connected by a web 13. Each head 12 has a wheel-wearing surface 110

12^d, wheel flange wearing surfaces 12^c, and a supporting surface 12^a adapted to rest on the base surface or seat 10^a. A central longitudinal rib 12^b is provided on the head adapted to lie within groove 10^b of the base. A soft metal liner 14 may be used between the supporting surface 12^a of the head and top surface 10^a of the base if desired. When the liner is used the rib 12^b is narrowed proportionately but, of course, the liner may be omitted and in that case the sides of the rib will be parallel and substantially vertical so as to closely fit the sides of the groove.

15 The shape of this head section is such that it has no laterally re-entrant projections and may be rolled in the position in which it is used on the rail so that the wheel wearing surfaces may receive the greatest pressure of 20 the rolls. In this connection, it is to be noted that the web 13 is inclined from the vertical thereby providing for efficient rolling of the same.

25 The head section has been designed to obtain the longest possible service before the same is replaced. Either head 12 may be seated upon the top surface of the base and the section may be used either on the inside or outside of the track. This provides four 30 interchangeable wheel wearing surfaces as will be apparent. This head section has also been designed to obtain additional strength in the rail. By having the heavy heads 12 connected by the web 13 the section 35 is made stiff when considered as a beam.

35 The flange wearing surfaces 12^c may have an outward slope as shown and a clip 15 having ridges 15^a, 15^b is adapted to bear at one end upon the outer surface 12^c and at 40 the other upon the outer leg of the U-shaped base 10. A bolt 16 having a nut 16^a thereon is provided to hold the clip in position. One of the ridges 15^b may be made larger than the other. When a head is changed in position so that a worn surface 12^c is presented 45 beneath the clip, the same may be reversed to place the large ridge 15^b at the top to securely hold the rail in position.

50 When desired a guard rail 17 may be secured to the rail by the same bolts 16 which serve to fasten the head section to the rail base.

55 Considering the foregoing construction, it will be seen that the head 12 rests upon the upper surface of the base 10 and consequently there is no tendency for the metal of the base to be sheared by the weight or downward force upon the head 12. Likewise the rectangular rib and groove construction between the head 12 and the base 10 together with the clips 15 forms a construction which very effectively secures the head to the base. It is evident that the clip 15 and rib and groove construction would resist lateral 60 thrust against the rail head which is the

principal force present tending to separate the head and base when a load passes. While the weight of the load serves to hold the head section down upon the base it is firmly held in position by the clip 15 and the wheel flanges prevent the head moving inward.

65 In Fig. 2 the base 20 shown is the same as that described in connection with Fig. 1 and consists of a U-shaped section having a top surface 20^a and groove 20^b. The clip 25 having ridges 25^a and 25^b and the securing bolt 26 are also the same. The head section 21, however, is in this case made from old rail. The head 22 with rib 22^b is cut from old rail and re-rolled to the desired shape. The rib 22^b which was cut from the web of the old rail is of the proper size to fit within the groove 20^b of the base and the supporting surface 22^a is adapted to fit the top surface 20^a of the base. The clip 25, as before, serves to hold the head to the base and to take outward lateral thrust tending to cause the head to overturn. The head section has two wearing surfaces as will be evident when it is stated that it may be turned around to expose the other edge of the top surface 22^a and other side face 22^c to the action of the wheels. In this figure the guard rail and soft metal liner have been omitted though their employment is optional.

70 In Fig. 3 it is seen that the base 40 having top surface 40^a and groove 40^b is the same as before. The head section 41, however, is somewhat different in sectional contour to provide for a modified fastening arrangement. The head section has a head 42 with wearing surface 42^a, support surface 42^a and rib 42^b as usual, but the side surfaces 42^c have flanges 42^e with inclined upper surfaces 42^f upon which clips 45 having inclined lips 45^c are secured by bolts 46 passing through the clips and base.

75 Fig. 5 shows a modification in which the base 30 is discontinuous and the sections of the same carried on each cross tie. Here the head section 31 with head 32 and web 33 provides sufficient stiffness for the traffic and continuous lengths of base are not necessary. Here also the clips 35 are made in much shorter lengths than where the base is continuous. For very light traffic a head section such as illustrated in Fig. 2 may be utilized with discontinuous sections of base.

80 Various modifications other than those illustrated and described are contemplated to be within the scope of the appended claims.

Having thus described the invention, what is claimed as new and desired to be secured by Letters Patent is:

85 1. In a compound rail, in combination, an inverted U-shaped base having a top surface comprising two inclined faces sloping to-

- ward the center and a rectangular groove along the center, a detachable head section having a support surface comprising two inclined faces sloping toward the center and 5 a rectangular rib along the center, said support surface of the head section being adapted to be seated on the top surface of the base, bolts extending through the legs of said base, and means engaged by said bolts for detachably securing said head section to said base. 10
2. In a compound rail, in combination, an inverted U-shaped base having a top surface comprising two inclined faces sloping toward the center and a rectangular groove 15 along the center, a detachable head section having a support surface comprising two inclined faces sloping toward the center, said support surface of the head section being adapted to be seated on the top surface of 20 the base, bolts extending through the legs of the base, and a clip positioned along one of the legs of said base and engaged by said bolts for detachably securing said head section to said base. 25
3. In a compound rail, in combination, an inverted U-shaped base having a top surface comprising two inclined faces sloping toward the center and a rectangular groove along the center, a detachable head section 30 having a support surface comprising two inclined faces sloping toward the center, said support surface of the head section being adapted to be seated on the top surface of the base, bolts extending through the legs of 35 the base, and a clip positioned along one of the legs of said base and engaged by said bolts for detachably securing said head section to said base, said clip being formed with inner ridges of different sizes at its upper and lower ends. 40
4. In a compound rail, in combination, an inverted U-shaped base having a top surface comprising two flat side faces joined by a rectangular groove in the center, a detachable head section having a support surface comprising two flat faces joined by a rectangular rib at the center, the supporting surface of said head section being adapted to rest on the top surface of the base portion, 45 a clip arranged on one side of the rail and engaging the sides of the base and top section, a guard rail having a flange arranged against the other side of the base section, and bolts passing through said clip and flange 50 and the legs of said base. 55
5. In a compound rail, in combination, an inverted U-shaped base having a top surface comprising two flat side faces joined by a rectangular groove along the center, a detachable head section consisting of two heads and a web connecting the heads on opposite sides, said web having an inclination from the vertical and lying along the side of one of the legs of the base, each of 60 said heads having its under surface shaped to fit the top surface of the base, and means to secure the head section to the base. 65
6. In a compound rail, in combination, an inverted U-shaped base having a top surface comprising two flat side faces joined by a rectangular groove along the center, a detachable head section consisting of two heads and a web connecting the heads on opposite sides, said web having an inclination from the vertical and lying along one of the legs of the base, each of said heads having a support surface comprising two flat side faces joined by a rectangular rib along the center, and a soft metal liner interposed between the support surface of one of the heads and the top surface of the base section. 75
7. In a compound rail, in combination, an inverted U-shaped base having a top surface including two flat inclined faces intersecting the side surfaces and sloping toward the center, a detachable head section having a support surface comprising two flat inclined faces sloping toward the center, said support surface of the head section being adapted to be seated on and substantially fit the top surface of said base, and means for detachably securing said head section to said base. 80
8. In a compound rail, in combination, an inverted U-shaped base having a top surface comprising two flat inclined faces sloping toward the center and a rectangular groove along the center, a detachable head section having a support surface comprising two inclined faces sloping toward the center and a rectangular rib along the center, said support surface of the head section being adapted to be seated on the top surface of the base, a clip extending along one side of said base and head section, and means for detachably securing said clip to said base. 95
9. In a compound rail, in combination, a base having a bottom support surface and a top head supporting surface, a detachable head section consisting of two heads and a web connecting the heads on opposite sides, said web having an inclination from the vertical, each of said heads having its under surface shaped to fit and adapted to rest upon the top surface of the base, and means to secure the head section to the base. 100
10. In a compound rail, in combination, an inverted U-shaped base having a top surface including two flat inclined faces sloping toward the center, a detachable head section consisting of two heads and a web connecting the heads on opposite sides, said web having an inclination from the vertical and lying along the side on one of the legs of the base, each of said heads having its under surface shaped to fit the top surface of the base and means to secure the head section to the base. 115
- In testimony whereof I hereunto affix my signature.

WILLIAM G. COUGHLIN.
